(57) **CLAIM**

The ornamental design for an electronic stethoscope chestpiece, substantially as shown and described.

DESCRIPTION

FIG. 1 is a perspective view of an electronic stethoscope chestpiece showing our new design;

FIG. 2 is a right side elevational view thereof; and the left side elevational view being a mirror image thereof;

FIG. 3 is a front elevational view thereof;

FIG. 4 is a rear elevational view thereof;

FIG. 5 is a bottom plan elevational view thereof; and,

FIG. 6 is a top plan view thereof.

The broken lines immediately adjacent the shaded areas represent the bounds of the claimed design while all other broken lines are directed to environment and are for illustrative purposes only; the broken lines form no part of the claimed design.
